UNITED STATES PATENT OFFICE.

HARRY F. ANDERSON, OF MARION, INDIANA.

DESIGN FOR A REFLECTOR FOR USE IN ILLUMINATED ADVERTISING-SIGNS.

42,723.

Specification for Design.

Patented July 9, 1912.

Application filed April 11, 1912. Serial No. 690,175. Term of patent 14 years.

To all whom it may concern:

Be it known that I, HARRY F. ANDERSON, a citizen of the United States, residing at Marion, in the county of Grant and State of Indiana, have invented a new, original, and ornamental Design for a Reflector for Use in Illuminated Advertising-Signs, of which the following is a specification, reference being had to the accompanying drawing, forming part thereof, and in which—

Figure 1 is a front elevation; Fig. 2 is a side elevation; Fig. 3 is a bottom plan view.

I claim:

The ornamental design for a reflector for use in illuminated advertising signs, as shown.

HARRY F. ANDERSON.

Witnesses:

WILLARD B. GEMMILL,
R. T. ST. JOHN.
